UNITED STATES PATENT OFFICE

63 LEO E. GOENEN AND JAMES A. GARROW, OF ST. PAUL, MINNESOTA, ASSIGNEES TO THE FRITZ-CROSS COMPANY, OF ST. PAUL, MINNESOTA, A CORPORATION OF MINNESOTA

CHAIR

Application filed February 25, 1929. Serial No. 342,449.

Our invention relates to chairs and has for its object to provide a chair having an adjustable back rest adapted to be simultaneously moved in up and down direction and in back and forth direction with respect to the seat.

Another object of the invention resides in providing said chair with a frame pivotally connected to said seat and with a lever pivoted to said frame, said lever having a forwardly extending arm adapted to support the back rest.

A still further object of the invention resides in providing a brace and in pivoting said brace to said seat and lever in a manner such that the said back rest moves simultaneously in an up and down direction upon back and forth movement of the said frame.

Other objects of the invention resides in the details of construction thereof and in the novel combination and arrangement of parts hereinafter illustrated or described.

In the drawing:

Fig. 1 is a perspective view of a chair illustrating an embodiment of our invention and showing the back rest moved into its most forward and lowermost position.

Fig. 2 is a side elevational view of the chair shown in Fig. 1 illustrating the back rest moved into its most rearward and uppermost position.

Fig. 3 is a side elevational view of a modification of the invention showing the back rest in its most forward and lowermost position.

Fig. 4 is a view similar to Fig. 2 of the structure shown in Fig. 3.

Fig. 5 is a fragmentary detail view of the bell crank lever and associated structure used with our invention with the locking bolt thereof removed.

Fig. 6 is a sectional view taken on line 6—6 of Fig. 5 illustrating the locking bolt in place.

In the adjustment of chairs employing adjustable back rests in which the back rest is adjustable in a back and forth direction and in an up and down direction, it has been found that to fit the chair to the user, a corresponding predetermined back and forward

adjustment is required with each up and down adjustment. The instant invention simplifies the adjustment of the back rests of chairs by combining the two adjustments so that upon properly adjusting the back rest for height, the same will be automatically moved into proper position with respect to the front edge of the seat to accommodate all users requiring the particular adjustment for height.

For the purpose of illustrating the application of our invention, we have shown a chair A of ordinary construction, which comprises four legs 10, 11, 12 and 13 attached to a suitable crown block 14 and flaring outwardly therefrom. These legs may have attached to them caster wheels 15 which serve the usual purpose. In the crown block 14 is mounted a standard 16 which carries a seat indicated in its entirety at 18. This seat comprises a seat supporting structure 17 to which the standard 16 is attached and which carries a cushion 19 of any suitable type. The seat supporting structure 17 may be of any desired construction which, in the form of the chair shown, includes two side members 20 to which the supports for the back rest proper are attached.

In conjunction with the seat 18, we employ a back rest 21 which is adapted to be simultaneously moved in up and down direction and in back and forth direction with respect to the seat proper and which is adapted to be oscillated to vary the angularity thereof. This back rest is mounted as follows: To the rearward ends of the side members 21 of the seat support 17 are pivotally connected by means of rivets 22, two spaced uprights 23 and 24 which, in the form shown in Fig. 1, are connected together by means of a tie bar 25 to form a U-shaped frame structure indicated in its entirety at 26. In addition to the uprights 23 and 24 we employ two braces 27 which are pivoted to the side members 20 of the seat support 17 intermediate the forward and rearward portions thereof by means of rivets 28 and which braces extend upwardly toward the upper portions of the uprights 23 and 24 and which

are connected to the back rest 21 in a manner to be presently described.

The back rest 21 has attached to the back 29 thereof two brackets 30 which have pivoted to them by means of rivets 31 the forwardly extending arms 35 of two bell crank levers 32. Bolts 33 pass through the bell crank levers 32 and the upper ends 34 of the uprights 23 and 24 and serve to hold the said 10 bell cranks in locked position with respect to the frame structure 26. The other arms 36 of the bell cranks 32 which extend in a more or less downward direction, are pivoted to the upper ends of the arms 27 by means of rivets 15 37.

The bolts 33 used for locking the bell cranks 32 with respect to the frame structure 26 are specially constructed to prevent the rotation of said bell cranks. This construction 20 is shown in detail in Figs. 5 and 6. A portion 38 of the shank of each of these bolts adjacent the head 39 thereof is constructed with longitudinal serrations which are adapted to fit into serrated holes 39 cut in the bell 25 crank 32 and in the upper portions 34 of the uprights 23 and 24. Nuts 40 screwed upon the shanks of bolts 33 serve to clamp the parts together. When the nuts 40 of the bolts 33 are sufficiently unloosened and the bolts 30 backed up through the holes 39 of the uprights 23 and 24, the serrated shanks thereof become disengaged from said holes which in such case engage the cylindrical part of the shank. When the bolts 33 are so disposed 35 the bell cranks 32 may be oscillated with respect to the frame structure 26. When the parts are in such position, the frame 26 may be grasped by the cross-bar 25 and the entire back rest supporting structure moved forwardly or rearwardly as required. Due to the braces 27 which are connected to the bell cranks 32, forward movement of the frame 26 causes the forwardly extending arms 35 of said bell cranks to swing downwardly and 40 to move the back rest 21 in a corresponding downward direction. Rearward movement of the cross-bar 25 causes the back rest 21 to be correspondingly raised. When the proper position has been determined, the nuts 40 45 of the bolts 33 may be tightened which causes the serrated shanks 38 to reenter the holes 39 in frame members 23 and 24 and deprive the said bell cranks of rotational movement, thereby securely locking the same in place. 50 For the purpose of facilitating the adjustment of the device, the rivets 22, 28, 37 and 31 are just sufficiently tightened to permit of the movement of the parts connected therewith without play. The rivets 31 are further 55 tightened to such a degree that the back rest 21 may be moved with respect to the supporting structure therefor about said pivots in a restrained manner so as to retain any adjusted angular position in which the same 60 is placed. If desired, spring washers may be 65

inserted between the bracket 30 and the bell crank 32 to assist in retaining such angular adjustment.

Although we have shown the locking device applied to the pivot between the bell crank and frame structure, it can readily be comprehended that the same may be applied to the pivot between the bell crank and brace instead. 70

In the form of the invention shown in Figs. 75 3 and 4, the bell crank illustrated in the other forms of the invention has been dispensed with and a straight lever 50 employed in place thereof. The remaining structure is identically the same as in the other form of the invention and the rivets 31 and 37 for attaching the bracket 30 and brace 27 to the raising and lowering device are positioned at the ends of the arms formed on said lever. The bolt 33 passes through the center of the lever 50 and is constructed identically the same as illustrated in Fig. 6 so as to hold the said lever 50 in adjusted position. The device shown in these figures is slightly simpler to construct and has slightly different movements than that shown in Figs. 1 and 2, though the range of movement is not quite as great as in the former. 80

The invention is highly advantageous in 85 that the proper adjustment of the back rest can be accomplished by a single movement of the back rest supporting structure. By positioning the back rest properly for height, the corresponding adjustment for position with respect to the front edge of the chair is 90 also automatically secured. The invention is extremely simple and effective and will not readily get out of order. The device is both attractive in appearance and highly serviceable. The chair is of sufficient strength and 95 rigidity and gives the user freedom of movement with proper back support. 100

Changes in the specific form of our invention, as herein disclosed, may be made within the scope of what is claimed without departing from the spirit of our invention. 110

Having described our invention, what we claim as new and desire to protect by Letters Patent is:

1. A chair comprising a seat, a frame pivoted to said seat and extending upwardly therefrom, a lever pivoted to said frame and having a forwardly extending portion, a back rest connected to said forwardly extending portion, and a brace connected to said seat and pivoted to said lever at another portion thereof. 115

2. A chair comprising a seat, a frame pivoted to said seat and extending upwardly therefrom, a lever pivoted to said frame, a brace pivoted to said seat and to one end of said lever, a back rest connected with the other end of said lever, and means for locking said lever against movement relative to said frame. 125

8. A chair comprising a seat, a frame pivoted to said seat and extending upwardly therefrom, a lever pivoted to said frame, a brace pivoted to said seat and to one end of said lever, a back rest connected with the other end of said lever, a bolt extending through said lever and frame for forming a pivot for said lever, and a nut on said bolt for bringing said bolt into clamping relation with respect to said lever and frame.

9. A chair comprising a seat, a frame pivoted to said seat and extending upwardly therefrom, a lever pivoted to said frame, said lever having a forwardly extending arm and a rearwardly extending arm, a back rest connected to said forwardly extending arm, and a brace pivoted to said rearwardly extending arm and to said seat.

10. A chair comprising a seat, a frame extending upwardly therefrom, means on the seat for guiding said frame for movement in a back and forth direction, a back rest at the upper portion of the frame, means on said frame for guiding said back rest for movement longitudinally with respect to said frame, and means for simultaneously moving said frame and back rest.

11. A chair comprising a seat, a frame extending upwardly therefrom, means for pivotally connecting said frame to said seat, a back rest at the upper part of said frame, a member connected to said back rest and extending rearwardly therefrom, means for pivoting said member to said frame, said means being disposed remotely from said back rest to guide the back rest for longitudinal movement with respect to the frame, and means for simultaneously swinging said frame and member about their pivots.

12. A chair comprising a seat, a frame extending upwardly therefrom, means for pivotally connecting said frame to said seat, a back rest at the upper part of said frame, a member connected to said back rest and extending rearwardly therefrom, means for pivoting said member to said frame, said means being disposed remotely from said back rest to guide the back rest for longitudinal movement with respect to the frame, and a brace pivoted to said seat forwardly of said frame and further pivoted to said member connected to the back rest rearwardly of the frame for simultaneously swinging said frame forwardly and said back rest downwardly.

13. A chair comprising a seat, a frame extending upwardly therefrom, means for pivotally connecting said frame to said seat, a back rest at the upper part of said frame, a bell crank pivoted to said frame and having a portion extending forwardly therefrom, a back rest pivoted to said portion of the bell crank and a brace pivoted to said seat and to the other portion of the bell crank for simul-

taneously swinging said frame and bell crank.

14. A chair comprising a seat, a frame pivoted to said seat and extending upwardly therefrom, a lever pivoted to said frame and having an arm extending outwardly therefrom, a back rest connected to said arm, said lever having a second arm operable concurrently with said first arm, and a brace connected to said second arm and to said seat for simultaneously swinging said lever and frame.

In testimony whereof we have affixed our signatures to this specification.
